PERCUSSION FUSE

Marc Birkigt, Bois-Colombes, France

Application November 15, 1935, Serial No. 50,048
In Belgium October 14, 1935

7 Claims. (Cl. 102—39)

The present invention relates to percussion fuses for shells or other projectiles and it is more especially, although not exclusively, concerned with fuses for shells of small calibre.

- 5 The object of the present invention is to provide a device of the type above referred to which can be manufactured in a simple and economical manner while ensuring perfect safety in the handling of the fuses and shells.
- 10 The essential feature of the present invention consists in arranging the fuse in such manner that it includes means for locking the striker in a fixed position with respect to the body of the fuse at least as long as the shell has not left the
- 15 tube of the firearm, said means being adapted to be automatically brought out of action by the slowing down of the shell as soon as it leaves said tube.

Other features of the present invention shall 20 result from the following detailed description of a specific embodiment thereof.

A preferred embodiment of the present invention will be hereinafter described, with reference to the accompanying drawing, given merely by 25 way of example, and in which:

Fig. 1 is an axial sectional view of an embodiment of a percussion fuse made according to the present invention;

Figs. 2, 3 and 4 are similar views of the same 30 fuse showing different characteristic positions of the parts;

Fig. 5 is a detail view, on an enlarged scale, of the general arrangement, in the relative position of the parts corresponding to Fig. 2.

35 According to the present invention, the percussion fuse is devised in such manner that its striker is locked in a fixed position with respect to the body of the fuse, at least until the shell leaves the tube of the gun, this locking action being exerted by means arranged to be automatically brought out of this locking position by the effect of the forces acting on the projectile when the latter has left the tube of the fire-arm.

For this purpose, the fuse according to the 45 present invention is provided with means capable of moving axially with respect to the striker and said means advantageously consist of two axial rings devised in such manner that, during the transportation and the handling of the projectile on which the fuse is fitted, they occupy a position in which they lock the striker with respect to the body of the fuse, and that, as soon as the shock of discharge takes place, both of these rings leave this position and occupy, under 50 the effect of inertia, a second locking position in

which they stay as long as the projectile is being moved inside the tube of the gun.

The sliding piece or ring which is positioned nearer to the body of the projectile is so devised, owing to the provision of a friction or other arrangement, as to be kept in this second mentioned position against the action of all the forces that normally act upon said projectile, but this arrangement permits said last mentioned piece or ring to come back into the first mentioned locking position in case of abnormal forces acting on the shell, for instance in the case of the shell being suddenly stopped inside the tube of the gun.

This friction or other holding arrangement 15 can advantageously be obtained by splitting this ring longitudinally, that is to say parallelly to its axis in such manner that it is tightly applied against the inner wall of its housing, or by providing said ring with hooking means capable of 20 being automatically released or deformed so as to enter suitable recesses provided in the body of the ring; whereby the latter can come back into its initial locking position in an abnormal case such as that above referred to.

On the contrary, the sliding piece or ring which is nearer to the head of the fuse is arranged in such manner that it is free to slide in its housing so that it can automatically leave its locking position when, after having undergone an 30 acceleration in the tube of the gun, the velocity of the projectile decreases, as is well known, immediately after said projectile having left said tube, whereby the last mentioned sliding piece or ring can move toward the head of the 35 fuse, away from the other ring provided, as above explained, with a braking or friction arrangement.

Elements, advantageously balls, urged by the effect of the centrifugal force developed by the 40 rotation of the projectile about its own axis, can then engage into the interval thus formed between the rings in such manner as to release the striker.

Of course, in the present description, when it 45 is stated that the striker is released and can strike the detonator, this relates to a relative movement of these parts with respect to each other, and includes the case in which the striker is rigidly fixed to the body of the fuse, this relative movement being produced by a displacement, with respect to the fuse body, of the detonator, locked and released in said body by the system above described.

50 Preferably, said striker or detonator is not pro-

55

vided with means, such as a spring, for urging it in a predetermined direction, so that the part (striker or detonator) which is released by the spreading apart of the balls or the like, is wholly free, on impact, to move toward the other of these two parts (detonator or striker) so as to produce the explosion of the shell.

In the example illustrated by the drawing, the body 1 of the fuse consists of a hollow metallic piece, carrying, in the usual manner, in line therewith, a base plug or chamber 2 in which are fitted the detonator 3 and primer charge 4. Against the open end of said plug 2 and between it and a corresponding shoulder of body 1, there is provided a fixed piece 5 having a hole 6 formed in its central part so as to afford a passage for the striker 7, which is guided in said hole 6.

The end of this piece 5 which is turned toward the head of the fuse carries a prolonged part 20 forming a cylindrical sleeve 8 the outer diameter of which is smaller than the inner diameter of the recess formed in body 1. In this manner, I provide between this sleeve 8 and body 1 an annular interval in which can be fitted a ring 9 capable of sliding axially in said annular space.

Ring 9 is so devised that its axial displacements are braked under normal conditions. For instance it is split at 16 longitudinally and given such a size and shape that it is strongly applied 30 against the inner wall of its housing.

In line with said ring 9 I provide, in the same housing, another ring 12, which is capable of sliding freely in both directions, parallelly to the axis of the fuse.

35 In the space existing between the free edge of sleeve 8 and an enlarged portion 10 of the striker 7, I fit masses, such as balls 11, held against the striker by either one or both of these two rings 9 and 12 (Figs. 1 and 2) as long as these rings 40 are located in adjacent relation to each other. As soon as these two rings are moved away from each other, they make it possible for balls 11, or equivalent means, to automatically engage 45 between them under the action of the centrifugal force developed by the rotation of the projectile about its axis, so that striker 7 is released.

Said striker 7 is provided at its outer end with 50 an enlarged part 13 which fits in a bore of restricted diameter of the head 14 of the fuse, said bore being closed by a lid 15.

The ogive-shaped, frusto-conical, or even cylindrical structure devised as above explained is of 55 a shape corresponding to that of ordinary fuses.

The fuse above described works in the following manner:

In the state of rest, the various movable parts included in the fuse structure occupy the position shown by Fig. 1, that is to say striker 7 is 60 locked in fixed position with respect to the body of the fuse by balls 11. The latter are prevented from moving laterally away from one another by rings 9 and 12, these rings being applied against each other by the fact that ring 9 is 65 tightly held in its housing. The projectile can therefore be transported and handled without any danger since the striker is positively prevented from moving axially. The unlocking of 70 said striker necessitates an axial displacement of ring 9, which can take place only under the effect of forces of inertia several hundred of times more important than those brought into play by any accidental shocks or vibrations as the projectile may undergo before the discharge in 75 the tube of the gun or before the time, determined

in the construction, at which the striker is to be released.

After introduction into the tube of the gun, under the effect of the recoil produced by the shock of discharge, inertia moves both of rings 9 and 12 into the position shown by Fig. 2, for which the upper edge of ring 9 is located below balls 11. Accordingly, in this position, ring 9 cannot in any way interfere with the subsequent outward displacement of said balls under the effect of the centrifugal force. But, in this position of Fig. 2, ring 12 prevents this outward displacement of balls 11.

Rings 9 and 12 occupy this position as long as the projectile is moving under normal conditions 15 inside the tube of the gun and there is no risk of premature explosion inside the gun.

In case of accidental stoppage of the projectile inside the tube, the whole of rings 9 and 12 moves very rapidly toward the front and the striker remains locked in position with respect to the detonator, the parts being immediately brought back into the initial position shown by Fig. 1.

When leaving the gun tube, the projectile undergoes, as it is well known, a certain reduction of 25 its velocity. Ring 12, which is free to move in its housing and which is not directly acted upon by the causes of this decrease of the velocity, keeps moving with the same velocity, that is to say moves in its housing toward the point or head of 30 the fuse. On the contrary, ring 9, which is axially held in its housing by friction remains in a fixed position with respect to the projectile and undergoes the same reduction of velocity as the latter. 35 Consequently, the two rings are moved apart from each other and balls 11, urged by the centrifugal force, automatically engage into the space thus left between said rings and accordingly release striker 7.

Of course, the time at which balls 11 release the 40 striker depends upon the time necessary for ring 12 to release said balls. The time at which the striker is released can therefore be varied by varying the length of the portion h of ring 12 45 that must move past the balls during the forward movement of said ring (see Figs. 2 and 5).

For the whole of the time during which ring 12 moves forward but balls 11 have not yet released the striker, these balls move with a helical motion 50 by rolling in contact with the inner wall of ring 12, which is besides given a relative rotary motion with respect to the body of the fuse. Consequently, it will be readily understood that the helicoids described by the balls are always similar 55 to themselves and that the number of turns made by the balls before they can escape radially remains the same for all fuses including similar constituting elements. Therefore all these fuses shall have the same delay to priming after the projectile has left the gun. There will be no risks 60 of premature explosions, which would be particularly dangerous in the case of a gun firing forward in the direction of the line of flight of an airplane flying at high speed, since the airplane 65 is moving right behind the projectile and has substantially the same trajectory as said projectile.

Advantageously, the edge of ring 12 which is located close to balls 11 is formed with a chamfer 70 17 or the like, corresponding for instance to an angle of 60°, whereby balls 11 can act, under the effect of the centrifugal force, for forcing rings 9 and 12 away from each other after the projectile has left the gun. In this case, this chamfer is preferably made of such a height that, when balls 75

11 occupy their locking position, they are in contact with the cylindrical surface of ring 12 when the latter occupies its characteristic position shown by Fig. 2. In this case also, by modifying 5 the interval h (Figs. 2 and 5) which is provided between the point of contact and the adjacent edge of the chamfer, it is possible to adjust in an accurate manner the time of priming of the fuse.

10 In consequence of the movement of the balls 11 away from one another, the striker is released when the projectile is moving along its trajectory, and, on impact, as shown by Fig. 4, said striker penetrates into the detonator due to a recoil or rebounding effect or due to the crushing of the 15 fuse head.

Such a fuse therefore meets all the particular requirements above set forth, and, while being very simple in its structure, very easy and cheap to manufacture and of very small size owing to 20 the small number of parts it includes, its safe working can be relied upon. The small size of this fuse makes it possible, for a projectile of a given size, to increase the efficiency of said projectile, since the charge thereof can be more important. 25

Furthermore, this fuse is perfectly fluidtight since its ogive is made of a single piece.

Of course the centrifugal masses which lock 30 the striker and then release it after the projectile has left the gun might, instead of balls, consist of juxtaposed and distinct elements of an annular whole of rectangular or circular, or even trapezoidal or triangular, cross section, whereby said 35 elements can engage in a wedge-like fashion between rings 9 and 12 for moving them apart from each other under the effect of the centrifugal force.

In a general manner, while I have, in the above 40 description, disclosed what I deem to be practical and efficient embodiments of the present invention, it should be well understood that I do not wish to be limited thereto as there might be changes made in the arrangement, disposition and form of the parts without departing from the 45 principle of the present invention as comprehended within the scope of the accompanying claims.

What I claim is:

1. A percussion fuse for a projectile to be fired 50 from a gun which comprises, in combination, a hollow fuse body having a cylindrical axial bore therein, a detonator fixed in said body at the tail end thereof, a striker axially movable in said bore having a portion of enlarged diameter, a 55 plurality of locking balls in an annular recess in said bore around said striker adapted, when held close to the axis of the fuse, to engage said enlarged portion of the striker so as to lock it axially, two rings fitting slidably in said bore 60 disposed in line with each other in the axial direction of said bore, stops in said bore for limiting the displacements of said rings in both directions respectively, the ring that is closer to the head of the fuse being freely movable in 65 both directions longitudinally of the fuse in said bore and constrained only by said other ring while the said latter ring is movable towards its own stop only in response to very high accelerations, such as that produced by the shock of dis- 70 charge in the gun, and is initially fixed in a position that keeps the ring closer to the head of the fuse applied against its respective stop toward the head of the fuse, said other ring being movable only in response to abnormal decelerations such as that produced by the shock caused 75

by the sticking of the shell in the barrel of the gun, said rings being adapted to keep said balls engaged against said enlarged portion of the striker as long as said rings remain in contact with each other, and to release said balls so as to allow them to move away from the striker under the action of a force tending to move them radially as soon as the ring that is closer to the head of the fuse is moved forward and apart from the other by the normal retarding of the velocity 10 of the projectile. 5

2. A percussion fuse according to claim 1 in which said second mentioned ring, that is to say the ring that is movable only in response to very high accelerations, is a split ring and is so shaped and dimensioned as to be strongly applied against the inner wall of said bore. 15

3. A percussion fuse according to claim 7 in which said element and said members are provided with means cooperating to force said members away from each other in wedge-like fashion as soon as the movement of said members away from each other has been started to a predetermined degree. 20

4. A percussion fuse according to claim 1 in which the first mentioned ring, that is to say the ring that is freely slideable in said bore, is provided with a chamfer along the edge thereof that is closer to the other ring, whereby said balls act in a wedge-like fashion to force said rings away from each other, as soon as the movement of said rings away from each other has been started to a predetermined degree. 25

5. A percussion fuse for a projectile to be fired from a gun which comprises, in combination, a hollow fuse body, two parts, one of which constitutes the detonator and the other the striker of the fuse, in said body, one of said parts being rigidly affixed to the projectile and the other being slidably attached to and movable longitudinally within the hollow fuse body, locking means for said movable part adapted to release it when left free to respond to the action of a force tending to move said means radially, two members movable inside said body disposed behind each other in the axial direction of the fuse, the member that is closer to the head of the fuse being freely movable in both directions longitudinally of the fuse and constrained only by the other member while the said other member is in frictional engagement with an element rigid with the body of the shell so that it is movable only in response to very high accelerations, of the kind of that produced by the shock of the discharge in the gun, said members being adapted to limit the radial movement of said locking means, thereby keeping said means in the operative locking position as long as said means and members are in contact with each other and to release said means when the member that is closer to the head of the fuse is moved apart from the other by normal decelerations of the velocity of the projectile, thereby allowing said means to escape from operative locking position into the space so provided between said members. 35 50 55

6. A percussion fuse for a projectile to be fired from a gun which comprises, in combination, a hollow fuse body, two parts, one of which constitutes the detonator and the other the striker of the fuse, in said body, one of said parts being fixed and the other axially movable therein, at least one locking element for said movable part capable of occupying either of two positions, one close to the axis of the fuse and 70 75

the other at a greater distance from said axis, said element being adapted, in its first position, operatively to engage said movable part and, in its other position, to release said movable part, 5 two members movable inside said body disposed behind each other in the axial direction of the fuse, the member that is closer to the head of the fuse being freely movable and constrained only by the other member, in both directions 10 longitudinally of the fuse, while the said other member is in frictional engagement with an element rigid with the body of the shell so that it is rearwardly movable with respect to the axis of the shell only in response to very high acceleration, such as that produced by the shock of discharge in the gun, and said other member having sufficient mass to overcome the friction of its 15 said engagement with the element rigid with the body of the shell in response to sudden deceleration, such as that produced by the sticking of the shell in the barrel of the gun, said members adapted to keep said locking element in its first mentioned position as long as they are in contact with each other and to allow said element to come into its second mentioned position, 20 under the action of the centrifugal force, as soon as one of said members is moved apart from the other.

7. A percussion fuse for a projectile to be 30 fired from a gun which comprises, in combina-

tion, a hollow fuse body, a detonator fixed in said body, a striker axially movable therein having a portion of enlarged diameter, a plurality of locking balls in said body around said striker adapted, when kept close to the axis of the fuse, to engage said enlarged portion of the striker so as to lock it axially, two members movable inside said body disposed behind each other in the axial direction of the fuse, the member that is closer to the head of the fuse being freely movable and constrained only by the other member, in both directions 10 longitudinally of the fuse, while the said other member is in frictional engagement with an element rigid with the body of the shell so that it is movable only in response to very high accelerations, of the kind of that produced by the shock of the discharge in the gun, said members being adapted to limit the radial movement of said locking means, thereby keeping said means in the operative locking position as long as said means and members are in contact with each other and to release said means when the member that is closer to the head of the fuse is moved apart from the other by normal decelerations of the velocity of the projectile, thereby allowing said means to escape from operative locking position into the space so provided between said members. 15 20 25

MARC BIRKIGT. 30
